UNITED STATES PATENT OFFICE

GRAHAM C. WOODRUFF, OF BRONXVILLE, NEW YORK, ASSIGNOR TO THE L. C. L. CORPORATION, A CORPORATION OF DELAWARE

SECTIONAL CARLOAD CONTAINER

Application filed August 14, 1930. Serial No. 475,804.

The object of my invention is to provide a sectional carload container primarily designed for handling wood logs and similar commodities, but its use is not thus restricted.

Referring particularly to pulp wood logs, under the present practice they are handled to and from a railroad car individually, which not only increases the cost of the logs but is a slow and tedious method of handling, and it is one of the objects of my invention to reduce to a minimum the cost of handling logs in shipment.

My container is designed to be loaded on railroad cars, preferably of the gondola type, and these cars may have rigid side walls or may, if desired have drop side walls.

Another object of my invention is to provide means for interlocking the containers with the car to hold them against shifting on the car while in transit.

Another object of my invention is to provide a container of such construction that the logs may be unloaded therefrom by gravity.

In the drawings:

Figure 1 is a top plan view of a car with one of my containers on it.

Figure 2 is a side elevation of Figure 1 with containers in dotted lines positioned thereon.

Figure 3 is a side elevation of my improved container.

Figure 4 is a top plan view of Figure 3.

Figure 5 is a detail sectional view on the line 5—5, Figure 3.

Figure 6 is an end elevation of my container mounted on a car, the car being shown in dotted lines.

Figure 7 is a perspective view of my improved container, parts being broken away.

Figure 8 is a detail vertical sectional view on the line 8—8 Figure 6, the car outline being omitted, and the latch being shown in elevation.

Figure 9 is an enlarged detail view of door hook and latch with the door in closed position.

Figure 10 is an enlarged detail view of

the container door hinge and immediately associated parts.

Figure 11 is an enlarged detail front elevation of the container door connection and joint between the end plates of the container.

The container is, preferably, of skeleton form as shown, but in any form it should be open at the top and have a slat bottom, the slat or cross beam bottom preventing the accumulation of waste material in the container and providing for drainage.

The end frame of the container is made up of two vertical corner posts 12, 13, and a horizontal cross beam 14 consisting of commercial angles, the cross beam 14 extending between the tops of the corner posts 12 and 13 and secured thereto by gussets 15. The corner posts 12 and 13 are securely riveted to the end sills 16 and further secured thereto by means of metal plates 17 which also function as backing plates for the door latch mechanism.

A horizontal steel stiffener 18, of pressed and flanged channel shape extends between the corner posts at a point substantially midway between the end sill 16 and top beam 14 and is securely riveted to each post, the base flanges of the stiffener being disposed toward the inside of the container.

To the inside face of the corner posts 12 and 13 and sill 16 and beam 14 steel sheathing 19 is attached, applied in two sections with a lap joint at the pressed steel stiffener 18 as clearly shown in Figure 7, said stiffener 18 functioning as a beam for the end plates.

It will be noted from Figure 9 than the outside flanges of the corner posts are turned outward, and that the inside face of each end wall of the container presents a smooth surface to the lading in the container.

The side construction of the container consists of a horizontal top beam 20, of commercial angle shape, extending between the corner posts and securely connected thereto by means of metal gussets 21, which also function as lifting link brackets to which the lifting links 22 are secured. A similar horizontal cross beam 23, located substantially half way up each side of the container is secured to the corner posts by

means of a suitable flat plate and gusset 24. Both beams 20 and 23 are commercial angles.

Extending vertically between the two beams 20 and 23 and spaced at regular intervals across the side of the container are pressed, flanged, channel shape braces or slats 25. Each brace laps the vertical flange of the members 20 and 23 and is securely riveted thereto.

10 The lower portion of each side of the container, from member 23 to side sill 26, serves as a door opening for discharging the lading.

15 The door for the container consists of a metal frame made up of commercial angles 27, 28, mitered (preferably) at the corners and connected by suitable gussets 29 (see Figure 11) and five (more or less) pressed flanged channel shape braces or slats 30 extending vertically between the top 27 and bottom 31 of the door.

20 The door is provided with suitable hinges 32 secured to the beam 23 and to the top member 27 of the door.

25 Metal guide shoes 32^a are secured to the door frame at each lower corner, said shoes or guides being riveted to gusset plates 33, said gusset plates, when the door is closed, overlapping the corner posts and sill 26 and thus functioning as door stops (see Figure 9). Guides 34 are secured to the car walls to cooperate with the guide shoes 32^a to hold the containers against shifting on the car. Each container, preferably, is held against shifting independent of any other container on the car.

30 To each corner gussets 33 is secured a latch hook 37 which projects through a slot (see Figure 7) in the outturned flange of each corner post of the container when the door is in closed position. On each end of the container opposite each latch hook 37 a suitable locking mechanism is provided to engage the hook 37 and hold the swinging side doors in closed position.

35 This locking mechanism consists of a latch 38 operated by gravity, a cam shaped latch pawl 39, and a latch housing 40 for securing these details of the end of the container in proper relation to each other and to the hook on the door.

40 The door locking mechanism is protected from damage by contact with other containers, by the outturned flanges of the corner posts and by the end gussets 17 to which each locking mechanism is attached.

45 These containers are designed primarily for handling pulp wood logs from a ship to a container and thence by rail to the paper mills.

50 Generally the loading, handling and unloading operation would be as follows:

55 Containers would be lowered into ship's hold and the logs thrown into the container

through the open top, or containers could be placed on a barge or on pier alongside of the ship and logs lifted from ship's hold and lowered into containers by means of the ship's tackle.

70 The containers would then be placed on a container car A, and hauled to destination and there removed from the car and placed at edge of inclined plane leading to a conveyor. Door latches would then be released, permitting door to swing outward due to pressure of the lading, and the lading would roll from the container down the incline to the conveyor. The unloading operation could be speeded up somewhat by lifting container by the two lifting links attached to the side of the container opposite the door to be opened.

75 This would throw the weight of the lading against the partly opened door, causing the door to open further, would incline the floor of the container, and would hasten the discharging of the load.

80 The bottom wall of the container is composed of slats 41 secured to the bottom sills 26 by brackets 43 in spaced relation. These slats are of commercial flanged shape. The spaced bottom slats 41 prevent accumulation of waste material in the container and provide for drainage, as this type of container 85 has an open top.

85 What I claim is:

1. A container of the character described having an open top and a slatted bottom and provided in a side wall thereof with a door opening upward and outward from said slatted bottom.

2. A container of the character described having an open top, waste vents through its bottom and a side door opening upward from the bottom of the container.

3. A container of the character described having an open top, slatted sides and bottom, imperforate end walls, and a door opening up from the bottom of the container.

4. A container of the character described having an open top and a slatted bottom, imperforate end walls, slatted side walls extending from the top of the container to a point substantially midway between the top and bottom of the container, and a door in each side extending from the bottom of the container to the said slatted side walls, and a lock for said door.

5. A container of the character described having an open top and a slatted bottom, imperforate end walls, slatted side walls extending from the top of the container to a point substantially midway between the top and bottom of the container, and a door in each side extending from the bottom of the container to the said slatted side walls, and a latch for said door, and lifting links at the upper corners of the container.

6. A container of the character described,

comprising corner posts, beams connecting said posts at their top and bottom ends, beams connecting the posts intermediate their ends, spaced slats connecting the intermediate beams to the top beams in two walls of the container, an imperforate wall connecting the said beams in two other walls of the container, a slatted bottom for the container, and a door secured to and constituting part of said slatted walls.

7. A container including corner posts, beams connecting said posts at the top and bottom, beams connecting said posts intermediate their top and bottom, spaced slats connecting the intermediate and top beams in two walls of the container an open work door structure hinged to the intermediate beams of the slatted walls, and extending to the bottom of the container.

8. A container including corner posts, beams connecting said posts at the top and bottom, beams connecting said posts intermediate their top and bottom, spaced slats connecting the intermediate and top beams in two walls of the container, an open work door structure hinged to the intermediate beams of the slatted walls, and extending to the bottom of the container, and a stop carried by the top adapted to engage one of the posts to limit the inward closing movement of the door.

9. A container including corner posts, beams connecting said posts at the top and bottom, beams connecting said posts intermediate their top and bottom, spaced slats connecting the intermediate and top beams in two walls of the container, an open work door structure hinged to the intermediate beams of the slatted walls, and extending to the bottom of the container, and a lock to hold the door in closed position.

10. A container including corner posts, beams connecting said posts at the top and bottom, beams connecting said posts intermediate their top and bottom, spaced slats connecting the intermediate and top beams in two walls of the container an open work door structure hinged to the intermediate beams of the slatted walls, and extending to the bottom of the container, and guide shoes carried by said door.

11. A container including corner posts, beams connecting said posts at the top and bottom, beams connecting said posts intermediate their top and bottom, spaced slats connecting the intermediate and top beams in two walls of the container, an open work door structure hinged to the intermediate beams of the slatted walls, and extending to the bottom of the container, and imperforate end walls secured to said top, bottom and intermediate beams.

12. A container including corner posts, beams connecting said posts at the top and bottom, beams connecting said posts inter-

mediate their top and bottom, spaced slats connecting the intermediate and top beams in two walls of the container, an open work door structure hinged to the intermediate beams of the slatted walls, and extending to the bottom of the container, and imperforate end walls secured to said top, bottom and intermediate beams, a latch hook carried by the door, and latching mechanism on said imperforate walls to engage the said hook when the door is in closed position.

In testimony whereof I affix my signature.

GRAHAM C. WOODRUFF.
